LOCK CONTROLLED ELECTRIC SWITCH

Ernest L. Teich, New Britain, Conn., assignor to
The American Hardware Corporation, New
Britain, Conn., a corporation of Connecticut

Application December 11, 1931
Serial No. 580,255

2 Claims. (Cl. 200—42)

The present invention relates to electric switches and more particularly to lock controlled electric switches, and comprises a new lock controlled switch of this type which may be operated by a master key as well as by a key individual thereto.

Heretofore one drawback of lock controlled electric switch was that it was not possible to operate a plurality of such switches by one and the same key, unless the locks of each were identical. Thus when a supervisor or the like in the course of his duties, was required to operate any one of a variety of different lock controlled switches, he could not use a master key but had to be provided with a different key for each lock. In accordance with the present invention a lock controlled electric switch operable by a master key as well as by a key individual thereto may be constructed by relatively simple modification of parts of standard devices. The new lock controlled switch comprises a snap switch of usual construction and of the oscillatory type, that is one which is turned in one direction to close, and turned in the opposite direction to open, and a lock having a set of pin tumblers and but one set of spring pressed drivers, including a master section in at least one of the tumblers, and lost motion means for permitting withdrawal of the key irrespective of whether the switch is open or closed.

For a better understanding of the invention reference may be had to the accompanying drawing of which:

Fig. 1 is a front view of a lock controlled electric switch embodying the invention;

Fig. 2 is a sectional view of the device of Fig. 1 taken along the line 2—2 thereof and showing a key in the lock;

Fig. 3 is a rear view of the lock taken along the line 3—3 of Fig. 2;

Fig. 4 is a front view of the lock with the cover removed and taken along the line 4—4 of Fig. 2; and

Fig. 5 is a front view of the switch taken along the line 5—5 of Fig. 2.

The particular embodiment of the invention illustrated in the drawing includes a snap switch enclosed in a casing 1 and adapted to be set into a wall in the usual manner of flush switches, and a lock enclosed within a cover 2 and carried by a plate 3. As the flush switch is a standard snap switch of oscillatory type only portions thereof, such as the movable contact arms 4, fixed contacts 5, springs 6 and operating shaft 7 have been illustrated. In accordance with the

invention the end of shaft 7 is threaded and a plate 8 is held in engagement with springs 6 by a nut 9. Relative rotation between plate 8 and shaft 7 is prevented in any suitable manner as by keying to the movable contact carrying parts of the switch. In the embodiment illustrated the plate 8 is provided with extending portions 10 which are cut away to receive projecting fingers 11 carried by the movable contact carrying disk 12. For operation of the switch by the lock plate 8 carries a projecting finger 13 which for convenience is stamped from the body of the plate so as to extend at right angles therefrom. Cooperating with finger 13 is a disk 14 rigidly mounted on the plug 15 of the lock and having two projections 16 and 16' thereon adapted to engage finger 13 upon rotation of the plug 15. Fingers 16 and 16', as shown in Fig. 3 are so spaced that, after plug 15 has been rotated in one direction or another to operate the switch by means of one or the other of fingers 16 and 16' sufficient lost motion is permitted for opposite rotation of the plug to key removing position at which time finger 13 is engaged by the other finger of the lock ready for operation in the opposite direction.

Plug 15 is provided with the usual tumblers 17 cooperating with spring pressed drivers 18 in the lock cylinder 19. Two of the tumblers 17 are sectionalized in the usual manner to permit of operation of the lock by a master key; the key 20 illustrated in Fig. 2 being, of course, the master key, not one individual to the particular lock illustrated. To prevent complete rotation of the plug by the key a stop 21 is carried by the lock cylinder 19 and a disk 22 rotatable with the plug 15 and cut away through an extended arcuate section is provided for engagement with the stop 21 at either end of the cut away arcuate section. In Fig. 4 is illustrated in full and dotted lines respectively the plug in position for removal or insertion of the key and in position corresponding to the greatest clockwise rotation permitted. In this latter position as shown in dotted lines stop 21 is in engagement with disk 22, preventing further rotation thereof in a clockwise direction.

The cover 2 of the lock has the usual opening therein for the plug. The words "on" and "off" are engraved or stamped upon the cover 2 together with a double headed arrow indicating the direction in which to turn the key for operating the switch.

It will be understood that the switch casing 1 may be enclosed in a suitable box sunk into a

110

wall or other fixture and that the lock may be secured to such a box by bolts or screws passing, for example, through holes 23 in plate members 24 fastened to the supporting plate 3. Preferably casing 1 is also mounted on plate 3 by means of the same screws utilized for fastening plate members 24 to plate 3 and indicated in Figs. 1 and 5 at 25. Screws 25 pass through aligned passages in casing 1 and in plate 3 and thread 10 into threaded holes in members 24, so as to prevent removal of the lock from the switch after installation of the casing within a wall. Any suitable apertured cover plate for covering all 15 of the device except the casing 2 may of course be provided; threaded holes 26 in members 24 being provided for securing such a plate into position.

When it is desired to open the switch, assuming it closed as shown in Figs. 2, 3 and 5, the 20 key 20 may be inserted when and only when the plug 15 is in the neutral position illustrated. When the key 20 is inserted in this position the tumblers 17 are raised into the position shown in Fig. 2 to permit rotation of the plug. Rotation 25 of plug 15 in a counter clockwise direction forces finger 16' carried by the plug against finger 13 of the switch to snap the switch into open or off position. The plug may then be returned to neutral position for removal of the key. When 30 in the neutral position, the switch being now off, finger 16 will be positioned adjacent finger 13 ready for operation of the switch in the opposite direction. If a key individual to the lock, instead of the master key 20 is used, the operation 35 will be the same except that the short master sections of two tumblers 17 will be forced up with the drivers in the usual manner.

The invention has now been described in connection with the preferred embodiment thereof. 40 Obviously various changes in the construction of the parts could be made without departing from the scope of the invention; the principal features thereof being the combination of an oscillatory snap switch with a lock operable by 45 a master as well as by an individual key and the provision of lost motion means between the

lock and switch for permitting withdrawal of the key after operation of the switch. As in lock controlled switches heretofore known the present device is so constructed that the switch and the member thereon which cooperates with the lock may be conveniently made by switch manufacturers and the lock and member thereon which cooperates with the switch may be made by lock manufacturers, thereby avoiding the necessity of constructing the entire device 85 at a single plant which would not ordinarily be provided with experts in both lines of manufacture.

The following is claimed:

1. A lock controlled electric switch comprising 90 in combination an oscillatory snap switch having an actuating member operable to open and close the switch upon rotation in opposite directions, a key operable plug having a single predetermined angular position at which a key may be 95 inserted and withdrawn, and connections between the plug and switch actuating member for thus rotating said member upon respectively turning the plug in opposite directions; said connections having provision for lost motion whereby by the plug may be returned to said predetermined angular position after operation thereof in either direction.

2. A lock controlled electric switch comprising 105 in combination an oscillatory snap switch having an axial actuating shaft, a disk carried by said shaft and keyed thereto, a projecting finger on said disk, a lock having a lock cylinder with a single set of drivers and a plug having a set of pin tumblers, including master tumblers, there- 110 in, a member carried on the rear surface of said plug, rotatable therewith and having a pair of projecting fingers, and means for so securing said switch and said lock together as to cause said finger on said disk to be engaged and moved by 115 one or the other of said fingers on said member when the plug is rotated by a key; said fingers carried by said member being so spaced as to permit return of the plug into key withdrawing position after operation of the switch. 120
